UNITED STATES PATENT OFFICE.

GEORGE W. PEASE, OF PITTSFIELD, MASSACHUSETTS.

GARMENT.

1,255,333.

Specification of Letters Patent. Patented Feb. 5, 1918.

Application filed June 13, 1916. Serial No. 103,371.

To all whom it may concern:

Be it known that I, GEORGE W. PEASE, a citizen of the United States, resident of Pittsfield, county of Berkshire, State of Massachusetts, have invented a certain new and useful Garment, of which the following is a specification.

This invention relates to garments such as overalls, pajamas, and the like, and has 10 for its object:

First. To produce a union garment having a back drop, which may be readily lowered or raised and fastened in place, and at the same time will permit the wearer to 15 bend forward or stoop without inconvenience.

Second. To render the back pockets readily accessible.

Third. To exclude dust, and 20 Fourth. To reduce liability of interference with machinery or other objects with which the user may come in contact.

These and further objects will more fully appear from the following specification and 25 accompanying drawings considered together or separately.

In the drawings Figure 1 is a rear view of a portion of a garment embodying my invention, showing the back drop raised.

30 Fig. 2 is a similar view, showing the back drop lowered.

Fig. 3 is a sectional view on the line 3—3 of Fig. 1.

Fig. 4 is a sectional view on the line 4—4 35 of Fig. 1.

Fig. 5 is a sectional view on the line 5—5 of Fig. 1.

Fig. 6 is a sectional view on the line 6—6 of Fig. 1.

40 Fig. 7 is a sectional view on the line 7—7 of Fig. 1.

Fig. 8 is a back view of a portion of the garment, showing a modification of the invention.

45 Fig. 9 is a sectional view on the line 9—9 of Fig. 8.

Fig. 10 is a front view, on a reduced scale, of the garment illustrated in Fig. 1, and

50 Fig. 11 is a detail of one form of fastening for supporting the extension of the back drop.

In all of the views like parts are designated by the same reference character.

In carrying out my invention I provide an upper part 1, in the form of a coat, jacket, 55 jumper or the like. To this upper part is attached the lower part 2, in the form of trousers, pants or the like. Both parts are provided with a front opening 3 which extends from the neck or collar down to the 60 crotch. One side of the front opening is connected to a side opening or slit 4, such slit being adjacent to the waist line 5. Only one slit is illustrated, but if desired two may be employed, one on each side of the front 65 opening, such as is illustrated in my co-pending application for patent filed February 1st, 1916, Serial Number 75,497. The front is closed by suitable fastenings, such as buttons. These fastenings also close the 70 ends of the slit or slits 4. The details of the front of the garment may be modified as desired, and a slit 4 is not essential and may be omitted if desired.

The lower part 2 is provided with a back 75 drop 6. This back drop 6 is provided with an extension 7. This extension is preferably made integral with the back drop. The extension 7 is adapted to be inserted inside of the back of the upper part 1 and to extend 80 upward a considerable distance. The back drop and extension are secured in place to the rest of the garment by suitable fastenings. At each upper corner of the extension or adjacent thereto is a suitable fastening 8. 85 In the embodiment chosen for illustration, this fastening is in the form of a button 8, coöperating with the buttonhole 8^a. Suitable means are provided for supporting the upper part of the back drop. In the embodiment chosen for illustration, these means consist of fastenings 9, 9, in the form of buttons engaging with buttonholes 9^a, such buttonholes being located at or about the line 5 of the waist. Additional fastenings 90 10, 10, are illustrated below the fastenings 9, 9. In the embodiment chosen for illustration these fastenings are in the form of buttons engaging with buttonholes 10^a, 10^a.

As an additional means of excluding dust 100 I prefer to use a dust excluding flap 11, which is secured to the inside of the back of the upper part of the garment above the upper end of the extension 7 (see Fig. 4). This dust excluding flap is not essential.

105 On the back of the back drop are the usual

back pockets 12, 12, one or more in number. At the side are illustrated the side pockets 13, 13. In the modification illustrated in Figs. 8 and 9 a side fly 14 is employed covering the fastenings 8, 9 and 10 and preventing them from engaging with machinery. In addition to the fastenings 8, 8 at the top of the extension I illustrate additional fastenings 15, 15, so that a snugger fit may be secured if desired. These fastenings are illustrated in the form of buttons. In Fig. 11 instead of a buttonhole I employ a clasp 16 adapted to engage with either of the buttons 8 or 15.

15 In use, the garment is put on by opening the front 3 and the slit 4 by disengaging the fastenings which hold the same in place. The legs may be then introduced into the lower part of the garment and the arms afterward introduced in the sleeves and the front opening 3 and slit 4 closed and fastened. The back drop is held up by the engagement of the buttons or fastenings 9 and 10 with their buttonholes, and the extension 20 7 is held up by the engagement of the buttons 8 or 15 with their appropriate supports which may be either the buttonholes 8^a or clasp 16, or equivalent device. When in such position the user may readily reach the 25 pockets 12, 12, without undoing any fastenings. He may also bend forward or stoop without thereby opening any part of the garment at the back and exposing the clothes underneath or admitting dirt or dust. This 30 is apparent from an inspection of Fig. 5 which is a section taken at about the waist line. When bending forward the body will bend along a line to the rear of the center, as for example along the line *a—a*. The 35 cross in the center of the line *a—a* indicates the approximate position of the spine. The 40 fastenings 8 and 9 are situated in front of the bending line *i. e.* the spine. As the body is bent forward on the line *a—a* Fig. 5 the 45 buttons 8 and 9 will be brought closer together causing the cloth between the buttons to be folded or puckered and this fold in the cloth will relieve the strains which would otherwise be put upon the cloth and 50 button securing means if the distance remained constant. The bending of the body forward will lengthen the line between the hips and shoulders of the wearer and raise the unfastened back portion of the lower 55 edge of the jacket portion 1 of the garment relatively to the back of the trousers portion and expose the clothing under the overalls if the extension 7 is not present. The extension, however, rising as it does a considerable distance above the lower extremity of 60 the back of the jacket will prevent the exposure of the garments and also when the wearer resumes an upright position will prevent them from bulging through the gap 65 formed between the jacket and trousers.

The extension being located inside of the body of the jacket and the lower edge of the back of the jacket fitting snugly the waist of the wearer there will be no loose skirt liable to be caught in moving machinery.

70 From the foregoing description it is apparent that I have succeeded in producing a garment which will have a back drop which may be lowered and which when elevated will be secured in position with the minimum number of fastenings and which will not require elastic attachment to compensate for changes in position of the wearer.

75 In accordance with the provisions of the 80 patent statutes, I have described the principle of my invention, together with the apparatus which I now consider to represent the best embodiment thereof; but I desire to have it understood that the apparatus shown is merely illustrative and that the 85 invention may be carried out in other ways.

Having now described my invention, what I claim as new and desire to secure by Letters Patent is:

90 1. A union garment comprising a coat and trousers permanently united at some place in the front, the rear of said coat portion terminating at approximately the waist line, a back drop, and an extension of said back drop, said extension extending up inside of 95 the back of the coat above the waist line, fastenings above the waist line connecting the upper corners of said extension to the coat at the sides of the latter, the upper edge of the extension being otherwise unsupported, detachable fastening means connecting the back drop to the coat portion at the waist line, and detachable fastening means for securing the back drop to the 100 trousers.

105 2. A union garment comprising a coat and trousers permanently united at some place in the front, the rear of said coat portion terminating at approximately the waist line, a back drop, and an extension of said back drop, said extension extending up inside of 110 the back of the coat above the waist line, and fastenings above the waist line connecting the upper corners of said extension to the coat at the sides of the latter, the upper edge of the extension being otherwise unsupported, and additional fastenings connecting the back drop to the garment at the waist line.

115 3. A union garment comprising a coat and trousers permanently united at some place in the front, a back drop, and an extension of said back drop, said extension being of a width equal to that of the back drop and extending up inside of the back of the coat 120 for an appreciable distance above the waist line, detachable fastenings connecting the upper corners of said back drop to the coat at the sides of the latter, the upper edge of the extension being otherwise unsupported.

ed, detachable fastenings for securing the sides of the back drop to the sides of the coat, detachable fastenings for securing the sides of the back drop to the trousers, and a dust excluding flap carried by the coat, the extension resting between the dust flap and the coat.

This specification signed and witnessed this tenth day of June, 1916.

GEORGE W. PEASE.
